UNITED STATES PATENT OFFICE

KENNETH B. WALTON, OF ATLANTIC CITY, NEW JERSEY

ANNUNCIATOR SYSTEM

Application filed May 15, 1929. Serial No. 363,332.

My invention relates particularly to a new and useful means for transmitting sounds from any one of a plurality of points to a single receiving point and there reproducing the sounds exactly but with some amplification to permit them to be heard clearly and distinctly, and may desirably be used in restaurants, hotels and the like for the transmission of orders of the guests from the place where given to the point from which the orders are filled, as in the transmission of dining room orders to the kitchen, though other uses and situations wherein my system may be found advantageous and desirable may readily be conceived.

A primary object of my invention is to save time and labor in the transmission of such messages, and to assure speed and accuracy in the receipt thereof by the person to whom they are directed, and in pointing out more fully the functions, construction and methods of operation of the invention reference will be had to certain embodiments installed and adapted for use in a large restaurant or hotel dining room and kitchen.

It will be understood that it is customary, in many institutions of the class mentioned, for the guests to express their desires verbally to the waiter or other dining room employee, who then goes to the kitchen and repeats the order to the proper kitchen employee by whom the order is filled. This method has not only the disadvantage of the danger of confusion and forgetfulness in the mind of the waiter, but also results in a delay, especially when the waiter on his way to the kitchen is detained by some intervening duty or other cause.

With a view to overcoming these and other disadvantages, a system has been used comprising the provision of a board in the dining room having a plurality of numbered push buttons, each wired to operate a correspondingly numbered signal in the kitchen such as a light or a pointer. When this system is employed, each order available to the guests must have a prearranged number by which it is known to the waiters and to the kitchen employees, so that an order can be transmitted by means of the waiter

touching the button the number of which corresponds to the prearranged number designating that order. The use of this system is accompanied by many difficulties and disadvantages, a number of which are obvious, such, for example, as the limitation to the number of different signals provided of the number and variety of possible orders available to the guests and also the inflexibility of the system which makes impossible the transmission of details of unusual requirements, as when a guest wishes his order prepared in a particular way requiring special instructions.

Briefly, my invention comprises a number of transmitting stations disposed at suitable points about the dining room, for example, where most convenient and accessible to those wishing to transmit an order to the kitchen and suitably interconnected with an amplifier unit and with a loud-speaking reproducing unit situated adjacent the kitchen or other point to which it is desired to transmit the orders, in combination with suitable visual signals the purposes of which will hereinafter appear, a push button or similar electrical contacting means being provided at each transmitting station whereby, among other things, the system may be energized and put in operable condition.

More particularly, the system is so constructed that when energized as a result of the push button being depressed at one transmitting station, a visual signal is displayed at all stations to indicate that the system is in use, and to warn others against attempting to transmit an order until the system is no longer being used by the first operator to whom appearance of the signal indicates readiness of the system for reception of his order. Other visual signals are also provided at the transmitting stations, the operation of which is controlled from adjacent the receiving point, by means of which the person receiving the message may acknowledge its receipt or otherwise signal the sender in accordance with a prearranged system, as, for example, to ask that the message be repeated. Thus it will be understood that by providing a sufficient number

of transmitting stations at convenient points, as about the dining room mentioned, it is possible for the waiter to repeat the order given by the guest within a few seconds, eliminating, to a large degree, the factor of forgetfulness and confusion in the mind of the waiter and also, due to the order being reproduced instantaneously in the kitchen, eliminating any appreciable lapse of time between the giving of the order by the guest and the commencement of the fulfilling of the order by the proper kitchen employee designated to that task. The work of the waiters is thus appreciably lessened, while, as trips to the kitchen for the giving of orders are entirely eliminated and the waiters are enabled to spend more of their time administering to the immediate desires of the guests, the service accorded the guests may be greatly improved.

My invention may also be used to great advantage in other circumstances where, as in the restaurant kitchen, it is desired to give a message to a workman without requiring that he interrupt his work in order to receive the message and without otherwise restricting his freedom to attend to his normal duties, especially when orders are to be transmitted from a number of diversified points to a single central point.

Other purposes, objects and advantages of my invention are hereinafter more particularly mentioned or will be readily apparent from the following more particular description of certain embodiments thereof as illustrated in the accompanying, somewhat diagrammatic, drawings, in which Fig. 1 is a diagram of the wiring of a preferred form thereof and Fig. 2 a diagram of the wiring of a somewhat modified form. Fig. 3 is a fragmentary sectional view in perspective of a typical restaurant or hotel dining room and kitchen, showing how my invention may be actually used therein, and Fig. 4 is a transverse vertical section of one of the transmitting units, one of which is comprised in each of the transmitting stations hereinbefore mentioned. Throughout the several figures like characters of reference are used to designate the same parts.

The circuits comprised in that form of the invention shown in Fig. 1 include the transmitting and amplifying circuit comprising an amplifying unit A of an ordinary type, any one of a variety of which may here be used, although I prefer, as having proved best adapted for the purpose, a unit comprising one rectifier and two amplifying vacuum electron tubes, which when connected in the usual manner with a suitable type of loud speaking reproducer will provide amplification sufficient to prevent the sounds reproduced being drowned out or made unintelligible by incidental sounds and noises being otherwise produced nearby. The ampli-

fying unit A is provided with electric current through the leads 1, 2 which may be connected to the ordinary commercial lighting circuit in the customary way. Connected to the amplifying unit by the leads 3, 4 is the loud speaking reproducer B which, when the system is in operation, reproduces, after amplification, the sounds received by the transmitter unit being used, electrical impulses from which reach the amplifying unit through the leads 5, 6 across which are connected in parallel a plurality of microphones 7 each in series with a separate push button 8, energy for the microphone-amplifier circuit being supplied by a storage battery 9 or other suitable source, the solenoid 10 of a relay R being connected in one of the main leads of the said circuit, as shown, for a purpose which will hereinafter appear. The use of the push buttons 8 or other contact-making means normally in open circuit position is advantageous in that the one giving an order is required to stand close to the transmitter to hold the circuit closed and more accurate transmission is thus assured than would be the case were it possible to give an order, for example, while walking past the transmitting station; additionally, the transmitting system is deenergized except when in actual use and electrical current is not wasted, while those near the reproducer are not continually annoyed by stray sounds received by the transmitter when the system is not in actual use for the transmission of orders. Each push button 8 is also so arranged that only such sounds as are received by the transmitter microphone of that transmitting station the push button at which is depressed, are transmitted and reproduced by the loud speaker, thus preventing the picking up of stray sounds by the other microphones during actual use of the system, and resulting confusion and indistinctness in the messages reproduced by the loud speaker are avoided.

It will thus be apparent that closing the switch of any of the push buttons 8 will complete a circuit through its associated microphone without, however, energizing the remaining microphones; consequently, the amplifier can receive signals from any microphone only when the push button switch associated with it is closed. It will also be readily understood that the completion of this circuit by means of any of the push buttons will energize the solenoid 10 of the relay R, and thereby close the relay switch 11 which, being in a circuit comprising the secondary coil 12 of a transformer T and a plurality of lights 13 connected in parallel across the leads 14 and 15 as shown in the diagram, will, when the primary coil 16 of the transformer T is supplied with current, as from an ordinary lighting circuit 17, 18, cause the lights 13 to light and remain light-

ed until, when the circuit through the solenoid 10 of the relay R is opened, the switch 11 again opens, breaking the circuit through lights 13. As one of the lights is placed 5 adjacent each unit comprising one microphone and the push button switch 8 in series therewith, it will be apparent that the lights serve as a signal at the transmitting units, showing by their being lighted that the 10 transmitting circuit is closed, and by their being unlighted that the system is available for use. I use the transformer T in the lighting circuits in order to save power consumption and permit the use of low voltage 15 wiring and lights, deriving power nevertheless from the relatively high voltage standard lighting circuit, but it will be understood that this feature is used merely for convenience as any power source or current 20 strength desired may here be used. Thus I have also shown interconnected with the low voltage leads 14 and 19 from the transformer T the lights 20, preferably of a distinctively different color from the lights 13 25 and of which one is associated with each transmitter unit above described. The lights 20, being in parallel, are so interconnected with the push button switches 21, also connected in parallel, that the closing of any 30 push button switch 21 will energize all the lights 20. Thus it will be understood that when these push buttons are disposed at convenient points adjacent the reproducer B, the employee receiving an order therefrom may easily light the lights 20 and thereby signal the order-giver, who is presumably standing near a transmitting unit and therefore near a light 20, as it will be understood that each transmitting unit 35 comprises one microphone 7, one push button 8, one light 13 and one light 20, together with suitable wiring as hereinbefore described, and that although I have herein shown and described lights as signals, other 40 suitable signaling means may be substituted therefor if desired.

In the alternative form of the invention shown in Fig. 2, parts which are the same in both forms are given in Fig. 2 the same 45 reference characters as in Fig. 1 but with the addition of a prime ('). In performing my invention in accordance with the form shown diagrammatically in Fig. 2, I have provided double pole push buttons 8' at the 50 transmitting units, whereby I am able to dispense with the relay R employed in my preferred form in Fig. 1, completing the circuit through the lights 13' by means of direct contact through the push buttons. As 55 it is believed that this arrangement of the wiring can be readily understood from the diagram in Fig. 2, having reference to Fig. 1 and the description thereof hereinbefore given, it is deemed unnecessary to describe 60 my alternative form any more particularly.

It will be understood that although I have shown in the drawings only a limited number of the transmitter units and of the signaling push buttons 21, a greater or less 70 number of either may be used according to the requirements of each case.

Also as to Fig. 3, where I have shown my invention in condition for actual use, it will be understood any number of transmitting 75 units C may be placed about the room in which it is desired to install my system, and may be connected in any suitable way, in accordance with the above description to the amplifier unit (not shown), the reproducer B and the push buttons 21; for example, 80 flexible cables may lead from socket connections in the wall to transmitter units mounted on movable stands, or the transmitter units may be mounted directly on the walls and the lead wires disposed between the 85 partitions of the walls.

Fig. 4 is a view of one form of my transmitting unit, showing for the sake of clearness but a small portion of the wires which in practice are connected to the various 90 parts. The casing 25 encloses the entire transmitting unit and when suitably supported in any convenient way, it may be made very compact and of a decorative appearance which will add to rather than detract from the favorable impression of the dining room received by guests. The front of the casing is provided with three apertures 26, 27, 28, one above the other, the center one 27 of which is somewhat larger than the others 26 and 28, which are of substantially the same size, being only large enough to permit observance therethrough of the lights 13 and 20 inside the casing, one light 95 being disposed substantially in registry with each aperture. In accordance with the above description of the wiring of my system, these lights may be of different colors to permit of their being easily distinguished; thus the upper light 13 may be 100 green and be connected as lights 13 in Fig. 1, while the lower light 20 may be white and be connected as the lights 20 in Fig. 1. The center aperture in the casing provides for the microphone 7, permitting the mouth-piece 29 to extend outside the casing while the diaphragm and casing of the microphone may be suitably secured within the 105 casing. I have found it advantageous that the mounting of the microphone within the casing be insulated against shock and vibration by some soft resilient material, such as sponge rubber, which prevents undesirable 110 vibrations, as those of the building, from reaching the microphone diaphragm. The flange 30 and post 31 form a convenient mounting for the transmitting unit, and when a hollow tube is used for a post mounting, the necessary wires may be carried 115 120 125 130

therethrough and thus improve the general appearance of the transmitting unit.

While I have herein described certain forms of my invention with considerable particularity, it will be understood that I do not thereby desire or intend to limit or confine myself specifically thereto as changes and modifications may be made in the form of the various elements and arrangement of the circuits, if desired, without departing from the spirit and scope of the invention as defined in the appended claims.

Having thus described my invention, I claim and desire to protect by Letters Patent of the United States:

1. In an annunciator system, the combination of an amplifier, a microphone circuit interconnected with said amplifier and including a source of current, reproducing means also interconnected with said amplifier, a plurality of transmitting microphones connected in parallel across said circuit, a switch interconnected with each microphone and adapted to normally interrupt the circuit therethrough, a normally open signal circuit including a source of current, a plurality of signals connected in parallel across said signal circuit, one of said signals being associated with each of the said microphones, and means adapted to close the signal circuit when any one of said switches is closed.

2. In an annunciator system, the combination of an amplifier, a microphone circuit interconnected with said amplifier and including a source of current, reproducing means also interconnected with said amplifier, a plurality of transmitting microphones connected in parallel across said circuit, a switch interconnected with each microphone and adapted to normally interrupt the circuit therethrough, a normally open signal circuit including a source of current, a plurality of signals connected in parallel across said signal circuit, one of said signals being associated with each of the said microphones, a relay adapted to close the signal circuit when any of said switches is closed to connect the microphone adjacent that switch to the amplifier, whereby all of said signals are energized simultaneously with the completion of the circuit through said microphone, a separate signal circuit connected with the source of current of the said signal circuit and having a plurality of signals associated with the individual microphones, and a plurality of switches for closing the said separate signal circuit located at different points within range of the reproducing means.

In witness whereof I have hereunto set my hand this 13th day of May, 1929.

KENNETH B. WALTON.
